UNITED STATES PATENT OFFICE.

WILLIAM MILES FOWLER, OF STAMFORD, CONNECTICUT.

BOTTLE-FILLING MACHINE.

SPECIFICATION forming part of Letters Patent No. 554,999, dated February 18, 1896.

Application filed November 19, 1895. Serial No. 569,379. (No model.)

To all whom it may concern:

Be it known that I, WILLIAM MILES FOWLER, of Stamford, in the county of Fairfield and State of Connecticut, have invented a new and useful Improvement in Bottle-Filling Machines, of which the following is a specification.

My invention relates to an improvement in bottle-filling machines in which one or more discharging-tubes arranged to enter the neck or necks of bottles is or are provided with means for automatically shutting off the discharge when the liquid reaches a predetermined height within the bottle or bottles.

My present invention is more particularly directed to means for cutting off the air-escape at variable heights, means for insuring the free escape of the air from within the bottle without liability of becoming choked from the passage of liquid through the air-vent, means for supporting the disk which closes the mouth of the bottle and for adjusting it relatively to the point of discharge, means for determining the height of the liquid in the distributing-reservoir and preventing it from entering the air-vent tubes from the fillers, and means for feeding bottles successively beneath the filling-tubes.

In the accompanying drawings, Figure 1 is a view of the machine in perspective. Fig. 2 is a vertical section from front to rear. Fig. 3 is an enlarged view in vertical section through one of the filling-tubes and the portion of the distributing-reservoir in proximity thereto. Fig. 4 is a transverse section through the line 4-4 of Fig. 3. Fig. 5 is an enlarged view in detail of the float and valve for closing the exit of air from the distributing-reservoir, and Fig. 6 is an enlarged view in detail of the dog for feeding the bottle-supporting carriage and means for throwing it into and out of engagement with the rack-bar on said carriage.

The form of supporting-frame which I have chosen at present for mounting the operative parts of the machine consists of a table A supported upon legs a, and standards B B' uprising from two opposite sides of the table A.

On the table A there is mounted a bottle-supporting carriage C for conveying the bot-

ties in banks successively beneath a range of fillers D. The bottle-supporting carriage C has imparted to it a step-by-step movement as follows: A rack-bar c is secured to and extends along the under side of the carriage. A dog E, provided with a mouth e for the reception of one of the teeth of the rack-bar c, is pivoted, as at e', to a clip e² fixed to a piston-rod F. The piston-rod F carries a piston f working within a cylinder f', fixed to the supporting-frame and provided with an air-vent f² at its end to serve as a dash-pot to relieve the shock caused by the stopping of the advance movement of the table. The clip e² is provided with a slot e³ within which a pin g, carried by the link G, slides. The link G is connected to one arm, h, of an angle-lever pivoted to a suitable hanger a' on the supporting-frame, as at H, its opposite arm having suspended therefrom a weight h' sufficient to rock the lever in a direction to return the dog E for a new hold of the rack-bar when the weight h' is permitted to act upon the angle-lever. The rod which forms a support for the weight h' is denoted by h² and is extended downwardly past the weight into a tube h³ pivotally secured at h⁴ to the foot-lever I. The foot-lever I is pivoted to the supporting-frame at a² and has an operating-treadle i. Intermediate of the free end of the tube h³ and a collar h⁶, fixed on the rod h², there is located a spring h⁵ which yields when the operating-lever I is forcibly lifted so as to give a gradual start to the rocking movement of the lever, pivoted at H, and so gradually start the bottle-supporting carriage C. The lever I is forced upwardly when released by the foot, after its downward movement, by a spring K of sufficient power to overcome the weight h' and impart to the carriage a prompt advance movement.

The dog E hereinabove referred to is provided with a projection e⁴ (clearly indicated in Fig. 6) which, when the pin g is at one end of the slot e³, rests upon the said pin and holds the dog up into engagement with the rack-bar c, as shown in Fig. 2, but when the pin g is at the opposite end of the slot e³ will permit the dog E to drop out of engagement with the teeth of the rack-bar c.

The operation of the feed is as follows:

- When the foot-lever I is depressed, the shaft h^3 is lowered and the weight h' is permitted to exert its force to rock the angle-lever pivoted at H. The first part of the rocking movement of the angle-lever will draw the link G in a direction to move the pin g to the opposite end of the slot e^3 and thereby permit the dog E to drop out of engagement with the rack-bar. The further rocking movement of the angle-lever will draw the dog E bodily along to the rear a distance sufficient to advance a succeeding bank of bottles beneath the fillers and at the same time draw the piston f away from the bottom of the cylinder f' .
- When the lever I is released and permitted to return under the tension of the spring K, the spring h^3 will at first be compressed, gradually lifting the weight h' and rocking the angle-lever in a direction to move the pin g on the link G to the front end of the slot e^3 , thereby engaging and lifting the dog E into engagement with the rack-bar, and the further upward movement of the lever I will move the dog E, and the carriage C with it, forward to the limit of its stroke, its arrest being gradual and gentle, because of the cushioning of the air between the piston f and the end of the cylinder f' .
- The range of fillers D, corresponding in number to the number of bottles in one of the banks carried by the carriage C, depends from a distributing-reservoir L mounted between the standards B to be vertically reciprocated. In the present instance I have shown the distributing-reservoir L attached to slides b, fitted to move on suitable ways on the adjacent faces of the standards B, the said slides b being connected by rods b' with the operating-lever I, so that when the operating-lever I is depressed it will lower the distributing-reservoir L and the range of fillers D connected therewith, and when the operating-lever I is released the distributing-reservoir L and the range of fillers depending therefrom will be lifted by the force of the spring K.
- The distributing-reservoir L is provided with a central dome l for the reception of a float l' , which, as the liquid in the reservoir L rises, will gradually lift, and when the liquid reaches a predetermined height will close the air-escape passage l^2 at the top of the dome by means of a valve l^3 connected with the float l' by a rod l^4 . The distributing-reservoir L has a suitable flexible connection l^5 with a source of supply. (Not shown.) The said reservoir L is further provided with a series of air and liquid tight caps l^6 projecting from its upper side and located over the fillers D, one over each.
- The fillers D consist of a tube d so plugged at its lower end as to provide a gradually-decreasing area or opening for the passage of liquid from the reservoir L, in order to finally direct the discharge to one side of the tube.
- The shape of the gradually-diminishing liquid-passageway is clearly shown in Fig. 4,

where it is denoted by d' , the plug which closes the lower end of the tube being denoted by d^2 . Within the tube d there is located an air-vent pipe, which, after it reaches a point some considerable distance above the lower end of the tube d—as, for example, the point d^3 —is open through to the exterior of the tube d, as clearly represented in the cross-section shown in Fig. 4, where the opening through to the exterior is denoted by d^4 . The lower portion of the air-vent pipe is denoted by M and is of smaller diameter than the upper portion, (denoted by M'), the latter being extended up through the distributing-reservoir L and into one of the air and liquid tight caps l^6 .

The air-vent extends to a point a considerable distance below the point where the liquid-discharge terminates, so that the air within the bottle may be free to escape, when the filler is inserted in the mouth of the bottle before any liquid is permitted to enter the bottle.

Around the filler-tube d there is located a vertically-sliding sleeve N, which covers both the liquid-discharge and air-vent when in its lower or normal position, and as it is slid upwardly first opens the air-vent and afterward the liquid-discharge.

The sleeve N has fixed thereon a collar n, which forms an abutment for the lower end of a coiled spring S, which surrounds the tube d, the upper end of said spring S bearing against an abutment n' at the upper end of the tube. The tension of the spring S tends to hold the sleeve N depressed and both the air-vent and liquid-discharge closed. Around the tube d there is also fixed a nut or screw-threaded collar n^2 , located in the present instance immediately below the collar n, and with this nut n^2 an interior screw-threaded sleeve O is engaged, which sleeve carries on its lower end an upwardly and outwardly flaring support o, against the lower or smaller end of which an elastic disk P rests. The elastic disk P is intended to close the mouth of the bottle, and the support o against which the disk P is pressed when the filler enters the mouth of the bottle, and is so shaped as to permit the elastic disk P to assume such shape as to perfectly conform to the rim at the top of the bottle, no matter what its irregularities may be, thereby securing an air-tight closure and at the same time preventing the disk from becoming wedged in the mouth of the bottle, an annoyance which has hitherto prevailed where the temporary closure was effected by a cork or plug which wedged itself into the mouth. It is intended that the disk P shall be of greater diameter than the opening in the mouth of the bottle, so as to cause it to rest on the rim, as distinguished from entering within the mouth.

The point at which the disk P shall engage the mouth of the bottle during the downward movement of the filler is determined by screwing the sleeve O up or down on the nut n^2 ,

thereby sliding the disk P farther away from or nearer to the lower end of the filler.

A socket-piece Q, fixed to the abutment n' beneath the distributing-reservoir L, may be made to loosely embrace the adjustable sleeve O, although this is not essential to the successful operation of the filler.

The trouble which has heretofore prevailed from the filling of the air-vent tube to a greater

10 or lesser extent with liquid during the operation of filling the bottle has been completely overcome by the enlargement of the interior of the vent-tube intermediate of the point where the air enters and leaves the tube, since

15 liquid which may creep up the portion of the tube of smaller diameter becomes suddenly expanded when it reaches the portion of the tube of larger diameter, and the air from beneath breaks through it and no longer carries

20 it along up with the current of air, and when the tube is withdrawn any small portions of liquid which may have crept up that portion of the tube of smaller diameter will rush back into the bottle.

25 The possibility of liquid within the distributing-reservoir entering the top of the vent-tubes is wholly avoided by extending their upper ends into air-tight caps l^o at the top of the distributing - reservoir, since no matter

30 how completely filled the distributing-reservoir may become, either intentionally or unintentionally, the moment the liquid reaches the top of said reservoir it will begin to compress the air within the caps l^o and will be held

35 by the compressed air in such caps against any liability of rising to the tops of the vent-tubes.

The operation of the machine is briefly as follows: The bottles having been arranged

40 in banks upon the carriage C and one of the banks brought beneath the range of fillers D, the fillers are caused to descend by foot-pressure upon the lever I. As the fillers enter the mouths of the bottles and engage the disks P

45 with the tops of the bottles, the air-vent first and then the liquid-discharge will be opened and the bottles will be filled up to a point corresponding to the lower end of the sleeve N, as this will be in effect the lower end of the

50 vent and up to the point where it is closed the liquid may rise. When the liquid is automatically cut off, the several fillers will be lifted from within the bottles, the air-vent and liquid-discharge being successively closed

55 by the action of the spring S as the fillers are withdrawn. The return movement of the lever I has, in the manner hereinabove fully set forth, advanced a second bank of bottles beneath the range of fillers, so that the lever

60 I may be again depressed to fill a second bank of bottles, as described.

It will be observed that as the air-vent is open for a considerable distance from its lower end the point at which it will be closed

65 and the discharge of the liquid arrested will depend upon the point where the bottom of

the sleeve N is located while the filling is taking place, and this may be varied by the adjustment of the disk P when nearer to or farther away from the lower end of the said 70 sleeve N. There is thus provided a very effective and simple means of determining the height to which the liquid shall be permitted to rise in the neck of the bottle.

What I claim is—

1. A filler comprising a liquid-conduit, an air-conduit extending to a point below the lower end of the liquid-conduit and means for successively opening the air and liquid conduits as the filler enters the mouth of a 80 bottle, the point where the air-vent is cut off by the rising of the liquid in the bottle being variable with respect to the lower end of the filler, substantially as set forth.

2. A filler, comprising a liquid-conduit, an air-conduit extending alongside the liquid-conduit and open at the side for a considerable distance from its lower end, a reciprocating sleeve forming a closure for the openings in the air and liquid conduits and means 90 for operating the sleeve as the filler enters a bottle whereby the air and liquid conduits are opened and the height of the air-escape opening determined by the position of the said sleeve, substantially as set forth.

3. A filler, comprising a liquid-conduit, an air-conduit, a movable part for opening and closing said conduits, a flexible disk secured to said movable part for covering the mouth of a bottle when the filler enters it, and a 100 support for the disk to hold it against the mouth of the bottle, said support being spaced from the disk opposite that portion of the disk which is intended to engage the rim of the mouth of the bottle, substantially as set 105 forth.

4. A filler, comprising a liquid-conduit, an air-conduit, a sliding sleeve fitted to surround said conduits, a screw-threaded collar fixed to said sleeve, an interior screw-threaded 110 sleeve, a disk surrounding the sliding sleeve and a back-support for the disk carried by the said screw-threaded sleeve, substantially as set forth.

5. A filler adapted to enter an opening in 115 a vessel and comprising a liquid-conduit, an air-conduit having a portion of a greater diameter than a lower portion whereby any liquid that may be caught therein will not clog the same, and means for closing the opening 120 in the vessel around the filler in advance of the completion of the movement of the filler into the vessel and for opening and closing the air and liquid conduits as the filler enters and is withdrawn from the opening in the 125 vessel, substantially as set forth.

6. The combination with a distributing-reservoir provided with an air-vent and with a range of air-tight caps projecting from its top, of a range of fillers depending from the 130 reservoir, air-vents extending from the fillers up within the air-tight caps on the reservoir

whereby liquid is prevented from entering said vents and a float for closing the air-vent in the reservoir, substantially as set forth.

7. The combination with the reciprocating fillers and the bottle-supporting carriage, of a main operating-lever for imparting motion to the fillers and carriage, a gravity-dog for advancing the carriage, a dog-operating lever

having a loose engagement with the dog, and a yielding connection between the said dog-¹⁰ operating lever and the main operating-lever, substantially as set forth.
